UNITED STATES PATENT OFFICE.

JOHN T. BARROW, OF CHICAGO, ILLINOIS.

LAMP-CHIMNEY.

SPECIFICATION forming part of Letters Patent No. 351,825, dated November 2, 1886.

Application filed March 22, 1886. Serial No. 196,058. (No model.)

To all whom it may concern:

Be it known that I, JOHN T. BARROW, of Chicago, Illinois, have invented certain new and useful Improvements in Lamp-Chimneys, 5 of which the following is a specification.

The object is to furnish a chimney made partially of metal and partially of glass, and provided with means for adjusting the draft; and the invention consists in the parts and 10 features hereinafter described and claimed.

The accompanying drawings illustrate the same.

Figure 1 is a perspective view. Fig. 2 is a vertical and Fig. 3 a horizontal section.

15 The chimney consists of a base portion, A, which is partially covered by a flat top, A', having a large opening in the center. On this is mounted a rectangular frame, consisting of uprights B, fastened to the top plate, and connected at the top by bars B'. On top of the frame is a cap, C, which is formed of a plate made to cover a large part of the upper opening of the frame, but leaving an opening in the center somewhat smaller than the opening 20 in plate A', and of vertical sides surrounding the opening and carrying it farther upward, like a flue. At the upper corners these sides are slit or beveled, as at c, so that the tops may be bent in more or less, to contract or 25 vary the size of the opening, for a purpose hereinafter explained. The cap is preferably hinged to the ends of two of the side bars, as at b, so that it may be swung off the top of the frame. When so hinged, the top bar may 30 be omitted from the side to which the cap is hinged.

All the parts thus far described are made of metal, preferably of brass, and the base portion A is adapted to fit onto the ordinary 40 burner of a kerosene-lamp, so that the central part of the burner holding the wick will project up about even with the plate A', the flame rising above it.

The uprights B are made of flat pieces bent 45 to form side flanges, b'. On the inside they are provided with projecting lugs or lips b'', adapted to hold sections of glass D, or other transparent substance, cut to fit between the uprights. When the cap C is removed or 50 turned back, the sections may be inserted from the top, being slipped in with the edges between the flanges and lips, or taken out for

cleaning. When desirable, a reflector may be substituted for or placed back of one of the sections.

55 By providing the chimney with means for varying the size of the flue more or less at the top it is adapted to different sizes of flame, and the shape of the flame, using the same width of wick, may be varied. If the top is opened to its full capacity, by bending the beveled parts out to a vertical position the volume of air-draft will be increased, and the flame be thereby made narrower and higher; but if, on the other hand, the opening 60 at the top is contracted, the air is thus regulated, and the flame is thereby made wider and not so high as under the condition first mentioned. Whatever be the theory, the varying of the size of the chimney-opening at the top 65 produces the above-named effects on the flame, and the advantage of better adapting the draft to any given size of flame is afforded by the use of the cap provided with means for varying the size of the top opening of the chimney. 70 The metal portion cannot be broken or destroyed by the heat of the flame, as the common glass chimney can, and is, therefore, comparatively indestructible, and with careful usage will last as long as the lamp. The glass 75 sections are easily made, and at trifling cost. They are, moreover, not so liable to be broken by the heat as a chimney made of one piece of glass, because the sections are permitted to expand separately. The metal portion, when 80 made of polished brass or ornamented, presents a very handsome appearance. For the purpose of ornamentation, additions may be put on any of the parts, as by extending the cap 85 farther down over the bars B', and curving or filagreeing it in any fanciful manner; also by extending the slit portion of the cap further upward and curving the extended portion outward in any tasty way. Such ornamentation, 90 however, should not change the essential structure, and would not constitute any part of the invention. For the purpose of relieving the cap somewhat from the heat of the flame, one of the sections D may be made shorter than the rest, as seen at d, to allow the cool air to 95 pass in under the cap.

100 It will be observed that the advantages secured by the cap provided with means for varying the size of the chimney-opening at the

top would be produced by such cap in combination with any common form of chimney, the cap being merely fitted to the top of the chimney.

5 What is claimed is—

1. As an improvement in lamp-chimneys, the combination of the metal base A, plate A', uprights B, bars B', cap C, with slits c at the top, and transparent sections D, substantially as and for the purposes specified.

2. The combination of a lamp-chimney with a cap, as C, of sheet metal, having upwardly-projecting sides surrounding the air-passage at the top of the chimney, provided with slits c, as and for the purpose specified.

JOHN T. BARROW.
